PUMP

Albert T. Bremser, Sidney, N. Y., assignor to
 Bendix Aviation Corporation, South Bend, Ind.,
 a corporation of Delaware

Application October 6, 1938, Serial No. 233,523

9 Claims. (Cl. 103—41)

This invention relates to pumping means and more particularly to liquid pumping apparatus, such as fuel injection pumps for use in solid fuel injection internal combustion engines.

In the operation of fuel injection pumps heretofore provided for internal combustion engines considerable difficulty has been experienced, by reason of the tremendous pressures and hence, velocities of the fuel, in preventing erosion of the metal walls of the fuel passages, particularly in the vicinity of the by-pass or cut-off port. The eroded metallic particles are drawn into the pump and tend to cause scoring of the pump cylinder and piston. The wearing away of the walls of the fuel passages also materially reduces the life of the pump and affects the efficiency of operation thereof. Difficulty has also been experienced in pumps of the character provided by the present invention in obtaining a smooth and consistent suction of fuel from the source of supply, this latter difficulty being caused, in part at least, by the turbulence of the fuel in the supply passages, particularly in the vicinity of the intake port of the pump, and by the breaking up of the fuel, in turn caused by the wire drawing thereof and by the same striking the walls of the fuel passages at high velocity.

It is accordingly one of the objects of the present invention to provide novel pumping apparatus wherein the above-mentioned difficulties are obviated.

Another object of the invention is to provide novel means in a fuel injection pump for reducing the turbulence of the fuel in the vicinity of the intake port thereof at the time of the suction stroke of the pumping plunger.

A further object is to provide a novel fuel injection apparatus which is so constructed as to minimize erosion of the fuel passages and the damaging effects thereof.

A still further object is to provide a novel fuel injection pump wherein proper lubrication of the plunger is insured at all times and wherein the pressures acting on the plunger are so directed as to obtain a good seal at the suction and by-pass ports.

Still another object is to provide a novel pump which will operate efficiently and satisfactorily for a longer time than similar pumps heretofore known.

The above and further objects and novel features of the invention will more fully appear from the following detailed description when the same is read in connection with the accompanying drawing. It is to be expressly understood, how- 55

ever, that the drawing is for the purpose of illustration only and is not intended to define the limits of the invention, reference for this latter purpose being had primarily to the appended claims.

In the drawing wherein like reference characters refer to like parts throughout the several views,

Fig. 1 is a side elevation, partly in section, of one form of pump embodying the present invention;

Fig. 2 is an outside elevation view of the pump shown in Fig. 1, as viewed from the right; and,

Fig. 3 is a sectional view of the pump casing, with parts broken away, the section being taken substantially on line 3—3 of Fig. 1.

A single embodiment of the invention is illustrated in the drawing, by way of example, in the form of a fuel injection pump assembly having a delivery valve incorporated therein. In the form shown, said pump assembly comprises a tubular casing 5 having laterally projecting ears 6 by means of which the same may be connected to an engine or other support (not shown). Mounted in casing 5 intermediate the ends thereof is a pump cylinder 7, the latter being supported on an internal shoulder 8 in the casing and held against rotary movement therein by a screw 9 which threadedly engages the casing wall and extends into an axially extending groove 10 in the cylinder wall. A pair of axially spaced ports 11 and 12 are provided in the walls of cylinder 7 adjacent the upper end thereof, as viewed in the drawing, for directing the flow of fuel to and from the cylinder in a manner to more fully appear hereafter.

Slidably extending into the lower end of cylinder 7 is a pump plunger or piston 13 which also functions as a slide valve for controlling the flow of fuel through ports 11 and 12. For a purpose which will more fully appear from a description of the operation which follows, plunger 13 is provided with an axially extending passage 14 and connecting radial passages 15 which continuously connect the upper end or pressure chamber of cylinder 7 to a pair of diametrically disposed helical grooves 16 and 17. Groove 16 cooperates with port 12 and constitutes a metering or cut-off groove whereas groove 17 serves as a lubricating and pressure balancing groove.

Means are provided for angularly adjusting piston 13 to change the relation between metering groove 16 and cut-off port 12 and thereby vary the effective pumping stroke of the piston.

In the form shown, said means comprises a sleeve 18 loosely surrounding the lower end of cylinder 7 in an enlarged portion of casing 5. Gear teeth 19 are formed on the upper end of sleeve 18 for cooperation with a rack 20 slidably mounted in casing 5, the movement of said rack being limited by a screw 21 which extends into a groove in said rack (Fig. 2). The lower end of sleeve 18 is axially slotted as at 22 for slidably receiving a cross-bar 23 rigidly connected to plunger 13. Sleeve 18 is held against axial movement relative to cylinder 7 by an internal shoulder therein which engages the lower end of said cylinder and an external shoulder which rests on the upper surface of an inwardly extending flange on a ring 24. The latter is positioned against a shoulder in casing 5 and held in place by any suitable means, such as a snap ring 25. It will thus be seen that by reciprocating rack 20, angular adjustment of sleeve 18, and hence plunger 13, may be effected without hindering the longitudinal or pumping movement of the latter.

Means are also provided for reciprocating piston 13 in cylinder 7 without subjecting the former to any lateral force or pressure which would cause unnecessary friction and binding. Said means, in the illustrated embodiment, include a tappet cup 26 slidably positioned in the lower end of casing 5 for engagement with an enlarged head portion 27 at the lower end of piston 13. The latter may be moved upwardly by means of a rotating cam (not shown) which engages the closed end of tappet cup 26 in a manner well understood in the art. The return or downward movement of piston 13 is effected by a spring 28 interposed between the flange of ring 24 and a slotted washer 29 which engages the upper shoulder of head 27.

The upper end or pressure chamber of cylinder 7 may be connected by any suitable means to an injection nozzle (not shown) in an internal combustion engine cylinder. The means shown for this purpose comprise an adaptor element 30 constituting a guide and seat for a delivery valve 31. Adaptor 30 rests upon the upper end of cylinder 7 and is held in fluid tight engagement therewith by a nipple or sleeve nut 32 which engages internal threads in the upper end of casing 5. A suitable packing washer 33 may be interposed between the inner end of member 32 and an external flange on adaptor 30 to further insure fluid tightness. The upper end of member 32 terminates in a threaded portion 34 having a passage 35 therein whereby a conduit (not shown) leading to a fuel injection nozzle of an engine cylinder may be attached.

Adaptor 30 has a central passage therein through which the flow of fuel from cylinder 7 into member 32 is controlled by delivery valve 31 which has a tapered head portion and a hollow stem. A seat is provided in the adaptor for the head of said valve and the upper end of the stem thereof is guided by the adaptor. The hollow center of said stem is always in communication through a plurality of radial passages 36 with an enlarged portion of the bore through the adaptor immediately above the valve seat. Valve 31 is normally held in closed position by spring 37 which is centered by tubular member 38 mounted in nipple 32 and having communication with passage 35.

In order to minimize erosion and the effects thereof and to insure smooth and consistent suction by pump 7, 13 novel means are provided in

casing 5 for directing the flow of fuel to and from cylinder 7 through ports 11 and 12. Preferably, said means are constituted by an insert or lining 39 of stainless steel or other hard metal, cast or otherwise fixed, in a peripheral groove or recess formed in casing 5. Lining 39 and said casing are provided with registering openings 41 and 42, respectively, which communicate with a source of liquid fuel supply (not shown) through conduits 43 and 44, said openings being spaced from and preferably diametrically opposite ports 11 and 12.

Lining 39 is channel-shaped in radial cross-section to provide a fuel passage around cylinder 7 and is provided with a radially extending internal rib 45 which engages the outer wall of cylinder 7 between ports 11 and 12 to thereby form a pair of grooves 46 and 47 in said lining, both of which grooves are in communication with fuel supply opening 41, 42. In the embodiment shown, rib 45 engages the wall of cylinder 7 throughout substantially half the circumference thereof and then tapers off as at 48 (Fig. 3) toward opening 41, 42.

To further insure against erosion adjacent cut-off port 12, a hardened steel screw 49 may be threaded into casing 5 with the pilot tip 50 thereof extending through insert 39 radially outward from said cut-off port 12. Screw or plug 49 may also be used as a vent plug when the pump is mounted in a horizontal position. A vent plug 51 is provided for this latter purpose when the pump is mounted in upright position. Screw 49 may also be replaced by pipe fitting 52 and this fitting connected to an outside conduit so that the fuel which is by-passed through port 12 may be returned to the fuel supply tank without first entering the supply line attached to fitting 44. In that case, internal rib 45 may completely surround cylinder 7 so that grooves 46 and 47 may communicate with each other only by way of ports 11 and 12, passage 14, 15 and groove 16.

In the operation of the above described pump, plunger 13 is reciprocated by suitable cam means and spring 28 in a manner well understood in the art and heretofore briefly described. On the upward movement of the plunger, as soon as the latter completely covers intake port 11, pressure is built up in the upper end of cylinder 7 which is sufficient to lift valve 31 off its seat. Continued upward movement of the plunger forces fuel past the head of valve 31 through ports 36 in the walls of the valve, the hollow valve stem and tubular member 38, and then through passage 35 to the injection nozzle. When the desired quantity of fuel has been injected into the engine cylinder, as determined by the angular setting of piston 13, metering groove 16 overlaps cut-off port 12 thereby permitting a free discharge of fuel and relieving the pressure in the pump, whereupon delivery valve 31 is closed by spring 37. The instant that groove 16 moves into overlapping relation with port 12 the fuel in the upper end of cylinder 7, passages 14, 15 and grooves 16 and 17, is under tremendous pressure. Accordingly, fuel is discharged through the small initial opening of said port at an extremely high velocity and strikes the walls of casing 5, 39. In pumps heretofore provided, this sudden rush of fuel through the initially small opening has resulted in erosion of the pump casing and a breaking up or atomization of the fuel as well as a setting up of a turbulence about the intake port and fuel sup-

ply passages which prevents smooth and consistent suction by the pump on the down stroke of the pump plunger, thus causing unequal and indeterminate quantities of fuel to be pumped to the engine cylinder.

The provision of the hard metallic insert 39 and hardened steel plug 49, 50 substantially reduces erosion caused by the discharge of high pressure fuel through cut-off port 12, and permits the use of light alloys, such as aluminum, for pump casing 5, and the provision of rib or partition 45 in said insert prevents the effect of fuel turbulence and of any broken down fuel on the suction of the pump hereby provided, since the turbulence of fuel in groove 41 does not materially affect the solid fuel supply in groove 46 adjacent intake port 11. Accordingly, after plunger 13 reaches the top of its stroke and is moved downwardly by spring 28, metering groove 16 first moves out of registry with port 12 so that further movement of the plunger creates a vacuum in cylinder 7. When the plunger uncovers intake port 11 the comparatively undisturbed solid fuel adjacent said port in groove 46 is drawn into cylinder 7 completely filling the space therein so that the pumping of a predetermined charge to the engine cylinder during the next upstroke of the pump piston is insured.

To vary the effective pumping stroke and hence the quantity of fuel pumped to the engine cylinder during each up stroke of plunger 13, rack 20 is moved to the right or left, as viewed in the drawing, to thereby angularly adjust sleeve 18 and hence plunger 13. It will be clear that angular movement of the latter changes the point in the upward stroke of the piston at which helical groove 16 begins to overlap cut-off port 12 and accordingly varies the effective pumping stroke of the piston. For idling, piston 13 is turned sufficiently in a counter-clockwise direction, as viewed from the top, so that groove 16 will register with port 12 during substantially the full upward movement of the plunger. Groove 17 is provided opposite groove 16 in plunger 13 to insure proper lubrication of the latter and a good seal at ports 11 and 12 during the effective pumping stroke. If groove 17 were not provided the pressure in metering groove 16 would press the plunger to one side and thereby break down the oil lubricating film on said side, as well as increase the clearance adjacent ports 11 and 12 and permit leakage of fuel under high pressure back into the supply line.

There is thus provided a novel fuel pumping apparatus which is so constructed as to operate efficiently and accurately over a long period of time. Novel means are provided whereby erosion of the fuel supply passages is minimized and the quantity of fuel pumped to the engine cylinder is not affected by turbulence or breaking down of the liquid fuel in the fuel passages. The novel pump provided may also be readily and inexpensively manufactured and installed.

Although only a single embodiment of the invention has been illustrated and described in detail it is to be expressly understood that the same is not limited thereto. For example, plug 49 may be eliminated, if desired, and groove 41 may be the only one which is provided with hardened metal walls. Other well known types of delivery valves and plunger actuating and adjusting means may also be employed. Various changes may also be made in the design and arrangement of parts illustrated, as will now be understood by those skilled in the art, without

departing from the spirit and scope of the invention. For a definition of the limits of the invention, reference is had primarily to the appended claims.

5. What is claimed is:

1. A fuel injection pump comprising a casing having an annular internal groove and an opening for connecting said groove to a source of fuel supply, a pump cylinder supported in said casing, said cylinder having two axially spaced ports in the wall thereof in communication with said groove at points diametrically opposite said opening, a metallic insert lining the walls of said groove and having an opening in registry with said first-named opening, a radially projecting rib in said insert engaging the outer wall of said cylinder between said ports for a substantial distance circumferentially of said cylinder on both sides of said ports, a hardened metallic plug threaded into said casing and extending through said insert in line with one of said ports, and a reciprocable plunger in said cylinder for controlling the flow of fuel through said ports.
2. In a fuel injection pump for solid fuel injection engines, a casing, a hard metal annular insert in said casing having a pair of circumferentially extending internal grooves therein, and an opening connecting said grooves to a source of fuel supply, a pump cylinder fixed in said casing and having a pair of ports, each of which communicates with a different one of said grooves at points circumferentially spaced from said opening, said grooves having gradually diminishing radial depths from opposed sides of said cylinder towards said opening and terminating at the sides of said opening, and a plunger in said cylinder for controlling the flow of liquid through said ports.
3. In a fuel pump for solid fuel injection engines, a casing having a pair of peripherally extending internal grooves therein and an opening connecting said grooves to a source of fuel supply, a pump cylinder fixed in said casing and having a port communicating with each of said grooves at points diametrically opposite said opening, said grooves having a gradually diminishing radial depth and merging into a single groove at said opening, and a plunger in said cylinder for controlling the flow of fuel through said ports.
4. In a fuel injection pump for solid fuel injection engines, a casing having a pair of peripherally extending internal grooves therein and an opening connecting said grooves to a source of fuel supply, a pump cylinder fixed in said casing and having ports connecting the bore of said cylinder with each of said grooves at points circumferentially spaced from said opening, said grooves having a gradually diminishing radial depth and merging into a single groove at said opening, and a plunger in said cylinder for controlling the flow of fuel through said ports.
5. Apparatus of the class described comprising a unitary metallic casing member having a bore therethrough and an annular internal groove therein intermediate the ends thereof, a hardened metallic ring filling said groove and having a pair of circumferentially extending internal grooves therein, said ring and casing member having connecting openings therein for connecting the grooves in said ring with a source of fuel supply, and a pump cylinder in said casing member having a port in communication with each of said last-mentioned grooves.

6. A fuel injection pump for solid fuel injection engines comprising a hollow casing having a circumferential recess in its inner wall intermediate the ends thereof, a peripherally extending ring of hard metal, such as steel, in said recess having two peripherally extending internal grooves and an opening connecting said grooves to a source of fuel supply, a pump cylinder having two axially spaced ports in the wall thereof and mounted in said casing with each of said ports in communication with different ones of said grooves at points circumferentially spaced from said opening, and a reciprocating plunger in said cylinder for controlling the flow of fuel through said ports.

7. In a fuel injection pump for solid fuel injection engines, a hollow casing having a peripheral internal groove intermediate the ends thereof, a channel-shaped annular insert of hard metal, such as steel, lining said groove, a pump cylinder in said casing, said cylinder having an inlet port and a discharge port, the latter having communication with said groove, means for connecting said intake port to a source of fuel supply, and a plunger in said cylinder for controlling the flow of fuel into and out of said cylinder through said ports.

8. A fuel injection pump for solid fuel injection engines comprising a cast hollow casing, an an-

nular insert of hard, wear-resisting metal, such as steel, fixed within said casing, said insert being internally grooved and having a radially extending passage therethrough in registry with an opening in said casing, a pump cylinder mounted in said casing and slidably extending through said insert, said cylinder having a port in the wall thereof in communication with the grooved inner periphery of said insert at a point circumferentially spaced from said passage, and a piston reciprocable in said cylinder for controlling the flow of fuel through said port.

9. A fuel injection pump for solid fuel injection engines comprising a hollow metallic casing, a hard metallic ring, such as steel, secured within said casing, said ring having a peripherally extending internal groove therein and a radially extending passage in the wall thereof connecting said groove with an opening in said casing, a pump cylinder mounted in said casing and extending through said ring in close contact therewith, said cylinder having a port in the wall thereof in communication with said groove at a position circumferentially spaced from said passage, and a piston mounted in said cylinder for reciprocation therein to control the flow of fuel through said port.

ALBERT T. BREMSER.
